UNITED STATES PATENT OFFICE

115,549

DESIGN FOR A STREET SIGN

Jesse Le Roy Greer, Dallas, Tex.

Application October 20, 1938, Serial No. 80,577

Term of patent 3½ years

To all whom it may concern:

Be it known that I, Jesse L. Greer, a citizen of the United States, residing at Dallas, in the county of Dallas and State of Texas, have invented a new, original, and ornamental Design for a Street Sign, of which the following is a specification, reference being had to the accompanying drawing, forming part thereof.

I claim:—

The ornamental design for a street sign, as shown.

JESSE LE ROY GREER.
